HEAT INSULATING STRUCTURE

Joseph L. Finck, Brooklyn, N. Y.

Application November 23, 1938, Serial No. 242,044

11 Claims. (Cl. 72—116)

This invention relates to a heat insulating structure for use in building constructions which may function either as a stiff insulating panel only or may function as a lath to receive and hold plaster in position and yet lose none of its efficiency as a heat insulator.

This invention particularly refers to improvements in the construction of such a commercially known building materials as "Metallated Ecod."

In the present construction of "Ecod," it is formed by corrugating metal-coated paper and piercing the corrugations with metal wire. These wires are then spot welded on the plain paper side to metal strips which run perpendicular to the wire but in the plane of the paper. The 15 piercing of the wire through the paper produces numerous open passages from the plain paper side to the metal coated side of the "Ecod."

When moist plaster or cement is applied to the plain side, the plaster may seep through these numerous holes or passages and cover the bright metal surface. The result is that the metal surface no longer serves as a heat reflector and insulator. Should the plaster contain slacked lime, the lime would tend to corrode the aluminum foil. From a heat insulation standpoint, the construction becomes entirely unsatisfactory.

A primary object of this invention is to provide several relatively simple constructions for such a metallated building material which is to function as a lathing for plaster in which the wire and metal strips are connected to the metal coated paper in such a manner that the paper is not pierced anywhere. Thus, its efficiency as an effective reflector and heat insulator is never marred when plaster is applied.

Another object of this invention is to provide simple and effective means on the plaster receiving side of this building material whereby the plaster is held in place in a more effective manner than heretofore.

Another object of this invention is to provide a building material of the character like "Ecod" which is flexible in one direction and may be rolled like a rug, thus facilitating its handling and transportation.

Another object of this invention is to provide an insulating building material which is stiff in at least one direction so that it may be more readily handled and positioned in the structure during the process of construction.

Numerous other important objects and advantages of this invention will become apparent as the description thereof proceeds, reference being had to the accompanying drawing, wherein:

Figure 1 is an end elevation showing somewhat diagrammatically one modification of the invention;

Fig. 2 is a plan view looking down on Figure 1; 5 Fig. 3 is a view similar to Figure 1 showing a modification thereof;

Fig. 4 is a view similar to Figure 1 showing another modification of the invention;

Fig. 5 is a plan view looking down on the modification shown by Fig. 4;

Fig. 6 is a view similar to Figure 1 showing still another modification of the invention;

Fig. 7 is a plan view looking down of the modification shown by Fig. 6; and

Fig. 8 is a view similar to Figure 1 showing another modification in which the building material of this invention is designed to be used purely as an insulating structure and not as a plaster base.

Figures 1 and 2 show a heat insulating structure which functions as a lathing for receiving and holding plaster. It is composed of a base material numbered 1 such as paper or cloth or any other suitable material. One side of the base material is provided with a foil coating 2 or any 20 suitable metallated reflecting surface which may be attached in any suitable manner, as by pasting, sewing or stapling. The reflecting surface may be a thin sheet of aluminum or other foil or may be metallic paint applied to the surface.

25 Periodically throughout the length of this sheet a ridge, fold or bend 3 is formed. These ridges together with the spaces between them form what may be termed corrugations throughout the whole length of the material. In order to stiffen the 30 ridges a long rigid metal strip 4 or one of any other suitable material is crimped, clamped or pinched tightly over each ridge. This strip is preferably extended along the whole length of the ridge. This construction thus provides a 35 rigid structure along the length of the ridges and a flexible structure along the length of the material at right angles to the ridges.

The modification shown in Fig. 3 is similar to that shown by Figure 1. In this modification, 45 however, the rigid metal strips, numbered 4', are provided with wings or prongs 5 which may be of solid metal throughout the length of the strip or perforated, or may be of punched and expanded metal such as is commonly used as lath. In fact, the entire metal strip 4' may be made of expanded metal, or any of the wired metal products. These wings extend into the spaces formed between the ridges and will thus function to key 50 the plaster more efficiently and effectively.

As is clearly indicated by Fig. 2, the material

of the construction of Figures 1 and 3 may be rolled up like a rug. This makes for ease in transportation and handling of the building material of this invention.

Figs. 4 and 5 illustrate another modification in which the final structure is rigid in all directions. As in Figure 1, the same base material 1, reflecting metallated surface 2, ridges 3 and rigid metal strips 4 are provided. Metal rods or wires 7 are arranged lengthwise of the material at spaced intervals across the metal strips 4 and are joined to the strips at points 8 by spot welding or any other suitable means of attachment. The wires 7 and strips 4 in this case serve as the plaster key.

The modification shown by Figs. 6 and 7 is similar to that of Figs. 4 and 5. The strips 4 in this case are made appreciably taller in cross section than the ridges 3. This provides a space above the ridges 3 so that the rods or wires 7 may pierce the strips 4 as indicated at 9 without piercing the ridges 3. The rods 7 may be welded or otherwise secured to the strips, if desired.

In both modifications shown by Fig. 4 or Fig. 6, the winged strips of the type shown by Fig. 3 may be used. The wings would thus provide additional keys for the plaster.

It will be noted that in all of the above constructions there is no piercing of the base material 1 or the metallated surface 2. Thus, it will be seen that if the base material is of a character that can prevent the seeping through of the plaster or water during the time that that plaster is applied and during the drying period, then the metallated reflecting surface will not be tarnished or corroded in any way.

The structure shown by Fig. 8 is one which is to be employed as a structural material where insulation only is required without the need for a plaster base. The base material 10 is the same as in the other modifications. This is provided with a metallated reflecting surface 11 on one side and a similar surface 12 on the other side. The ridges 13 and strips 14 are the same as in Figure 1. Thus, there is provided an insulating structural material that is rigid in one direction and so may be more readily handled during its application.

If rigidity in such an insulating material is desired in all directions, a construction like that shown by Figs. 4 and 6 may be employed.

The metallated building material of this invention finds utility in many places in a building structure, where heat insulation is required and where a plaster or stucco base and effective key therefor, as a substitute for ordinary lath, is required.

In an ordinary exterior wall, the material of this invention would be nailed to the spaced uprights with the metallated surface facing the air space in the wall. The other side faces the inside of the room and is immediately ready to receive the plaster for finishing the interior wall.

On the outside of an exterior wall, if it is to function as a base for stucco, the material of this invention would be nailed to the spaced uprights with the metallated surface facing inward toward the air space. The other side would face the exterior for receiving the stucco.

This invention may also be used similarly on ceilings and on the inside of the roof structure.

When insulation only is required, the construction shown by Fig. 8 would be used. The stiffening rods crimped to the two sided reflecting surfaced sheet would aid in positioning and handling it during erection.

It is thus seen that I have invented a material of construction that is a marked improvement over that heretofore used. It will not lose its insulating efficiency when it is in place and will act as a plaster base to retain the plaster in position more effectively than the material heretofore used.

I claim:

1. In a construction material of the character described, a base material, a reflecting coating material on said base material forming an integral reflecting and insulating sheet, said sheet including the base material and coating material being bent at spaced intervals to form ridges and stiffening members arranged on one side of said sheet extending along said ridges and maintaining said ridge form.

2. In a construction material of the character described, a base material, a metal coating on one side of said base material forming an integral reflecting and insulating metal-coated sheet, said sheet including the base material and coating material being formed with ridges, and stiffening means extending along and crimped to said ridges.

3. In a construction material of the character described, a base material, a metal coating on one side of said base material forming an integral reflecting and insulating metal coated sheet, said sheet including the base material and coating material being formed with corrugations at spaced intervals, rigid strips extending along and crimped to said corrugations of said sheet whereby said sheet is stiff in one direction and flexible in a direction at right angles thereto.

4. In a construction material of the character described, a base material, a reflecting coating material on said base material forming an integral reflecting and insulating sheet, said sheet including the base material and coating material being formed with corrugations at spaced intervals, rigid strips arranged on one side of said sheet and extending along and crimped to said corrugations, said strips having wings thereon extending into the spaces between the corrugations.

5. In a construction material of the character described, a base material, a reflecting coating material on said base material forming a reflecting and insulating sheet, ridges formed on said sheet at spaced intervals, stiffening members connected to said ridges, and rods connected to said stiffening members, said stiffening members and said rods being arranged wholly on one side of said sheet.

6. In a construction material of the character described, a base material, a reflecting coating material on said base material forming a reflecting and insulating sheet, ridges formed on said sheet at spaced intervals, stiffening members arranged on one side of said sheet connected to said ridges, rods arranged at spaced intervals along the length of said stiffening members, said rods being connected integrally to said stiffening members.

7. In a construction material of the character described, a base material, a reflecting coating material on said base material forming a reflecting and insulating sheet, ridges formed on said sheet at spaced intervals, stiffening members connected to said ridges, rods arranged at spaced intervals along the length of said stiffening members, said rods piercing said stiffening members without breaking said base material.

75 8. In a construction material of the character

described, a base material, a metal coating on one side of said base material forming a reflecting and insulating metal coated sheet, corrugations formed on said sheet at spaced intervals, stiffening strips connected to said corrugations, and rods piercing said strips at right angles thereto without breaking said base material.

9. In a construction material of the character described, a base material, a reflecting coating on said base material forming an integral reflecting and insulating sheet, said sheet including the base material and coating being bent at spaced intervals to form ridges, and stiffening members extending along said ridges and maintaining said ridge form.

10. In a construction material of the character described, a base material, a reflecting coating

on said base material forming a reflecting and insulating sheet, ridges formed on said sheet at spaced intervals, stiffening members extending along said ridges and maintaining said ridge form, and rods connected to said stiffening members arranged crosswise thereof.

11. In a construction material of the character described, a base material, a metal coating on one side of said base material forming an integral reflecting and insulating metal-coated sheet, said sheet including the base material and coating material being formed with ridges, and expanded sheet metal having channel-shaped portions forming stiffening means extending along and crimped to said ridges.

JOSEPH L. FINCK.
